UNITED STATES PATENT OFFICE

159,887

DISPLAY CASE

Milo J. Belsky, Oklahoma City, Okla.

Application September 3, 1949, Serial No. 4,848

Term of patent 14 years

(Cl. D80—11)

To all whom it may concern:

Be it known that I, Milo J. Belsky, a citizen of the United States, residing at Oklahoma City, in the county of Oklahoma and State of Oklahoma, have invented a new, original, and ornamental Design for a Display Case, of which the following is a specification, reference being had to the accompanying drawing, forming part thereof.

Fig. 1 is a perspective view of the front and side of a display case showing my new design;

Fig. 2 is a perspective view showing the opposite side of the display case;

Fig. 3 is a rear elevational view; and

I claim:

The ornamental design for a display case, as shown.

MILO J. BELSKY.
